JOHN B. SPERRY, OF AURORA, ILLINOIS, ASSIGNOR TO THE AMERICAN WELL WORKS,
OF AURORA, ILLINOIS, A CORPORATION OF ILLINOIS.

PUMP.

1,379,704.

Specification of Letters Patent. Patented May 31, 1921.

Application filed May 17, 1918. Serial No. 235,107.

To all whom it may concern:

Be it known that I, JOHN B. SPERRY, a citizen of the United States, and a resident of Aurora, in the county of Kane and State 5 of Illinois, have invented certain new and useful Improvements in Pumps, of which the following is a specification, reference being had to the accompanying drawings.

This invention relates to improvements in 10 deep well pumps of the type employing two plungers, the two rods connected respectively with the plungers being located one within the other and being adapted to be separately reciprocated and preferably in 15 such manner that the upward stroke of each plunger will be caused to begin before the other plunger has quite reached its uppermost position. It is the principal object of this invention to provide improved means 20 for insuring the maintenance at all times of a water-tight joint at each of the bearings for the inner one of the reciprocating plunger-rods. It is of the greatest importance that such joints be so maintained for in the 25 event of admission of water to the interior of the outer hollow rod the water so admitted will surge up and down during the pumping operation and seriously reduce the efficiency of the pump. Briefly stated, I ac- 30 complish the above-named object by securing opposite the joints between the sections of pipe that constitute the outer plunger-rod a packing box that forms a bearing for the inner rod, and providing means for so con- 35 necting together the several sections of the inner rod in a manner different from that employed in connecting together the several sections of the outer hollow rod that any tendency of either rod to turn axially will be 40 effectively counteracted by the other rod, with the result that the packing-boxes and the packing material held by them around and against the inner rod cannot be disturbed. It is further an object of the inven- 45 tion to provide a construction that in addition to furnishing perfectly maintained bearings for the inner plunger-rod will pro- 50 vide effective means for retaining within the outer tubular rod the desired quantity of hard grease or other lubricant employed for lubricating the rods; and to improve generally the construction and operation of pumping means of this general character. These objects are attained by the construc- 55 tions and arrangements of parts shown in

the drawings and hereinafter particularly described.

In the drawings:—

Figure 1 is a vertical central section through portions of a pump cylinder and a portion of the main supporting pipe at the upper end thereof, the view showing also the upper one of the plungers and the two plunger-rods; and

Fig. 2 is a similar view showing a portion 65 of the pump cylinder that extends below that part of the cylinder shown in Fig. 1. In this said lower portion is shown the lower plunger and a portion of its actuating rod.

Referring to the drawings,—10 indicates 70 the lower portion of a pipe which forms the main support for the pump cylinder. As will be understood, it is to be supported with its upper end at or near the surface of the ground and provided with a lateral dis- 75 charge for the water being pumped. 11 indicates the pump cylinder secured to the open lower end of the supporting pipe 10 by a screw-threaded coupling 12. 13 indicates a plunger movable within the cylinder 11 80 and provided with a suitable packing 14, as usual. This plunger 13 is the upper one of the two that are employed and it is carried at the lower end of a hollow plunger-rod indicated by 15. As shown, the connection 85 of the plunger 13 to its said rod is made through the medium of a coupling 16 which is screwed upon the upper end of a sleeve 17 formed with and rising from the plunger 13 and into which coupling the threaded 90 lower end of the hollow rod 15 is screwed. This coupling, in the construction shown, has a right-hand thread, and the object in so making it will be described later on. The valve that controls the water passage through 95 this plunger is indicated by 18. It is mov- ably mounted on the sleeve 17 and is held to its seat by a spring 19 that abuts at its upper end against the lower face of the coupling 16. The hollow rod 15 will be 100 made up of a plurality of sections secured together by suitable couplings each having a right-hand screw thread as in the case of the coupling 16. One of such couplings is shown in Fig. 1 and indicated by 20. 21 105 indicates a packing-box provided at one end with an annular flange 22 that extends out so as to fit between the ends of two sections of the hollow plunger-rod 15 and thus hold the packing box firmly and centrally of the 110

hollow rod when the sections of said rod are firmly screwed together by the coupling 20. 23 indicates a gland screwed into the packing-box to hold a suitable packing 24 5 around the other plunger-rod.

Such other plunger-rod is partly cylindrical and partly angular in cross-section, the former portion being indicated by 25 and the angular part by 25^a. It is cylindrical throughout the greater portion of its 10 length and hence reciprocates freely in its bearings furnished by the cylindrically-bored packing boxes 21. The angular portion 25^a is at the lower end of the rod and passes through and is reciprocatable in the correspondingly shaped opening in the upper plunger 18 and its attached sleeve 17. 15 Such angular portion 25^a will be made of sufficient length to always remain in its said bearing in the plunger during the full 20 length of the stroke of the plungers. The rod 25—25^a is preferably made solid, as shown. The lower end of the angular portion 25^a is connected to the lower plunger 26, 25 the connection in the construction shown being by means of a threaded shank formed with such member 25^a, such shank entering a threaded socket formed in a sleeve 28 that rises from and is integral with the plunger 30. As shown, such sleeve is also exteriorly threaded at its upper end to receive a nut 29 that acts as an abutment for the upper end 35 of a spring 30 that bears against the valve 31 that controls the water passage through said plunger. 32 indicates packing around the plunger. The inner plunger-rod, like the outer hollow one, is made up of sections which are coupled together. They are coupled together by means of a standard left-hand hollow coupling 33 engaging left-hand threaded nipples 34 formed on the ends of the rod sections. 35 indicates a suction-pipe secured by a coupling 36 to the lower end 40 of the cylinder 11.

45 By the construction shown and described it is evident that the provision made for connecting the sections of one of the plunger-rods by right-hand screw-thread means while the sections of the other rod are connected by left-hand screw-thread means serves to effectually counteract any 50 tendency to separation of the joints of either rod since each rod is held against rotary movement with respect to the other. For 55 example, with the parts arranged as shown, but with the inner plunger-rod having its sections coupled together by right-hand screw-thread means the same as are the sections of the hollow rod, the effect of a 60 movement of such inner rod that tended to loosen it at its connection with the lower plunger 26 and loosen the connections of its several sections would also tend to unscrew 65 the plunger 13 from its connection with the lower end of the outer plunger-rod 15 and

also loosen the connections between the several sections of such rod. With the two rods, however, coupled up in a reverse manner, as shown, any rotary movement in a direction tending to unscrew the connections 70 of one rod will cause a tightening of the connections of the other rod, as will be appreciated when it is borne in mind that the angular portion of the inner rod has a perfect sliding fit through the correspondingly 75 shaped opening in the upper plunger 13.

Inasmuch as any tendency to rotary movement on the part of either of the rods is thus effectually provided against, it follows that the several packing-boxes will remain undisturbed and that the packing that each contains will be at all times held with the desired degree of tightness around and against the inner reciprocating rod, and 80 thus not only will leaks around the joints 85 of the sections that constitute the outer rod be prevented but the hard grease or other lubricant with which such sections are provided will be effectively maintained to furnish the desired lubrication of the inner rod. 90

While I have described the outer rod sections connected together by right-hand screw-threaded means and the sections of the other rod connected together by left-hand screw-threaded means, it is obvious, of course, that the reverse of such arrangement might be employed—it being only necessary in order to accomplish the desired end that the sections of one rod be screwed together in an opposite manner from those of the 100 other rod. By the use of my construction by which the hollow pump-rod sections 15 are prevented from unscrewing from the couplings 20, the packing boxes 21 are held continuously in fixed position. In this way 105 there is no chance that the packing become disturbed or that communication be established between the interiors of adjoining sections 15 about the rod sections 25.

What I claim as my invention and desire 110 to secure by Letters Patent, is—

1. The combination of a pump-cylinder, two reciprocating plungers therein, one above the other, a hollow sectional plunger-rod connected with the upper plunger, a 115 second plunger-rod within the hollow plunger-rod and extending through said upper plunger and connected with the lower plunger, said inner plunger-rod having an angular portion and a cylindrical portion, 120 and two bearings for said inner plunger-rod, one of said bearings being in the upper plunger and the other being supported between two sections of the hollow plunger-rod, one of the bearings being angular 125 and the other cylindrical to correspond to the two different shapes of the said inner plunger-rod.

2. The combination of a pump-cylinder, two reciprocating plungers therein, one 130

- above the other, a hollow plunger-rod connected with the upper plunger, a second plunger-rod within the hollow plunger-rod and extending through said upper plunger and connected with the lower plunger, said inner plunger-rod having an angular portion and a cylindrical portion, and two bearings for said inner plunger-rod, the lower one of said bearings being in the upper plunger and the upper one supported by the hollow plunger-rod, one of the bearings being angular and the other cylindrical to correspond to the two different shapes of the said inner plunger-rod, that one of the bearings through which the cylindrical portion of the inner rod passes comprising a packing-box located adjacent to the joint between two sections of the hollow plunger rod.
3. A deep-well pumping means comprising two reciprocating plungers and a rod for each plunger, one rod being within the other and extending through the upper plunger, means for interlocking said pumping means to prevent independent rotary movement of either of the rods or plungers, and packing-boxes supported at intervals by the outer rod around the inner rod.
4. A deep-well pumping means comprising two reciprocating plungers and a rod composed of sections for each plunger, one rod being within the other and having an angular portion that passes through and reciprocates in a correspondingly-shaped bearing in the upper plunger and having also a cylindrical portion that reciprocates in another bearing,—said other bearing consisting of a packing-box having a flange projecting between adjacent ends of two sections of the outer rod—and screw-threaded means for securing the sections of the two rods together, the screw-threaded means for one rod having a right-hand thread and that for the other rod having a left-hand thread.
5. In a deep-well pump, the combination with two reciprocating plungers and a rod for each plunger, each rod being formed of a plurality of sections and one rod being within the other and extending through the upper plunger, of a packing-box having a flange projecting between the ends of two adjacent sections of the outer rod, said packing-box forming a bearing for the inner rod, screw-threaded means for securing the sections of each rod together, the screw-threaded means for one rod having a right-hand thread and that for the other rod having a left-hand thread, and means for interlocking said rods together to prevent independent rotary movement of either rod.
6. The combination of a hollow pump-rod formed of a series of sections joined tightly together, a second pump-rod extending through said hollow pump-rod, packing boxes effectually blocking off the space about said second pump-rod within one hollow pump-rod section from that of the adjacent hollow section, said packing boxes being held firmly in position by the rigid joining of said hollow sections, and means for preventing the loosening of the joints of said hollow pump-rod.
7. The combination of a hollow pump-rod formed of a series of sections joined together by screw-threaded couplings, a second pump-rod extending through said hollow pump-rod, packing boxes effectually blocking off the space about said second pump-rod within one hollow pump-rod section from that of the adjacent hollow section, said packing boxes being held firmly in position by the hollow sections screwed tightly into said couplings, and means for preventing the loosening of said couplings on said hollow pump-rod sections.
8. The combination of a hollow pump-rod formed of a series of sections joined together by screw-threads, a second pump-rod extending through said hollow pump-rod and also formed of a series of sections joined together by screw-threads, packing boxes effectually blocking off the space about said second pump rod within one hollow pump-rod section from that of the adjacent hollow pump-rod section, said packing boxes being held firmly in position by the screw-threaded joints of said hollow pump-rod being maintained in tightened condition, and means for preventing the sections of each of said pump-rods from becoming loosened by rotary movement with respect to each other, the screw threads of one pump-rod being right-hand threads and those of the other pump rod being left-hand threads.

JOHN B. SPERRY.
